F. J. KOLSON.
COMBINED SCRAPER AND SMOOTHER.
APPLICATION FILED FEB. 17, 1913.

1,061,085.

Patented May 6, 1913.

UNITED STATES PATENT OFFICE.

FRANK J. KOLSON, OF MCKEESPORT, PENNSYLVANIA.

COMBINED SCRAPER AND SMOOTHER.

1,061,085.

Specification of Letters Patent. Patented May 6, 1913.

Application filed February 17, 1913. Serial No. 748,976.

To all whom it may concern:

Be it known that I, FRANK J. KOLSON, a citizen of the United States of America, residing at McKeesport, in the county of Allegheny and State of Pennsylvania, have invented certain new and useful Improvements in Combined Scrapers and Smoothers, of which the following is a specification, reference being had therein to the accompanying drawing.

This invention relates to a combined scraper and smoother especially designed for the use of brick-layers and cement and concrete workers.

15 The primary object of my invention is to provide a novel tool having detachable smoothing members of various shapes and contours, whereby the tool can be used by brick-layers or cement workers for producing beads, joints or surfaces of various contours.

20 Another object of this invention is to provide a combined scraper and smoother with a detachable and adjustable member that permits of grooves of various depths and cross sectional area being produced by an artisan working with mortar, plaster, concrete, cement or other plastic material.

25 A further object of this invention is to accomplish the above results by a strong and durable tool consisting of comparatively few parts that are easily assembled and highly efficient for the purposes for which they are intended.

30 With the above and other objects in view the invention resides in the novel construction, combination and arrangement of parts to be hereinafter specifically described and then claimed.

35 Reference will now be had to the drawing, wherein:

Figure 1 is a side elevation of a tool in accordance with this invention, Fig. 2 is a longitudinal sectional view of the same, Fig. 45 3 is a plan of the tool, Fig. 4 is a cross sectional view of the same, Fig. 5 illustrates cross sectional views of portions of smoothing or shaping members, and Fig. 6 illustrates similar views of other members.

40 A tool in accordance with this invention comprises a metallic saddle 1, having the lower longitudinal edges thereof provided with lateral flanges 2. The saddle 1 has an inclined front wall 3 provided with a longitudinal slot 4, and the top of said saddle terminates in a rearwardly directed exten-

sion 5 that serves functionally as a handle for manipulating the tool. The side walls of the saddle 1 are in parallelism and detachably mounted between the side walls of said saddle and engaging the front and top walls thereof is the blade 6 of a smoothing, scraping or shaping member 7. The lower edge of the member 7 terminates in a head having the forward end thereof upturned, as at 8 whereby said member can be easily moved over a surface and in some instances, the lower edge of the member 7 has a convex portion 9, which facilitates moving the member around a corner of plastic material to smooth the same, without any danger of the material being upset by the action of said member.

45 The blade 6 of the member has a T-shaped slot 9^a and arranged in said slot is the head 10 of a bolt 11, said bolt extending through the slot 4 to be held therein by a winged thumb nut 12 screwed upon the outer end of said bolt. It is through the medium of the bolt 11, the nut 12 and the slot 4 that the blade 6 of the member can be raised and lowered within the saddle, whereby the lower edge of the member will be correctly positioned relatively to the lateral flanges 2 of the saddle.

50 Connected to the lateral flanges 2 of the saddle by bolts 13 and nuts 14 are the lateral flanges 15 of angle guide members 16 that are arranged longitudinally of the saddle. These guide members have the forward and rear ends thereof upturned, as at 17 whereby the tool can be easily shifted back and forth.

55 As illustrated in Figs. 5 and 6, the lower edge of a member can terminate in a head especially designed for producing a bead, joint or angle. For instance a semicylindrical head, a semicylindrical groove, a groove V-shaped in cross section, a dove-tailed groove or a rounded corner can be produced, and for this reason the smoothing and shaping member has been made detachable whereby a member especially designed for a certain piece of work can be used in connection with the saddle.

60 For brick-layers, the guide members 16 ride upon the surface of bricks while the members scrape and smooth the mortar between the bricks, in some instances producing a groove between the bricks that imparts the desired effect to a brick wall.

65 For concrete workers, the marking of

blocks in a cement pavement and the rounding of corners can be easily accomplished without resorting to a kit of special tools.

From the foregoing it is thought that the utility and operation of a tool in accordance with my invention will be apparent without further description, and while in the drawing there is illustrated a preferred embodiment of my invention, it is to be understood that the structural elements are susceptible to such variations and modifications as fall within the scope of the appended claims.

What I claim is:—

15 A tool of the type described comprising a saddle having an inclined slotted front wall, a handle carried by the top of said saddle, a

shaping member having a blade extending into said saddle, means connected to said blade and extending through the slot in the front wall of said saddle for adjustably holding said blade whereby said member can be correctly positioned relatively to the lower edges of said saddle, and longitudinal guide members connected to the lower edges of said saddle and having upturned ends.

In testimony whereof I affix my signature in the presence of two witnesses.

FRANK J. KOLSON.

Witnesses:

KARL H. BUTLER,
MAX H. SROLOVITZ.
